UNITED STATES PATENT OFFICE.

FRANK E. LUMLEY, OF CHICAGO, ILLINOIS.

SWITCH-CONTROLLING DEVICE.

Application filed March 25, 1927 Serial No. 178,474.

This invention relates to certain novel improvements in controlling devices and particularly to devices of this kind adapted to control pressure or vacuum systems. The specific embodiment of the invention herein shown and described is adapted for usage to control a vacuum cleaning system.

It is among the objects of my invention to provide a controlling device which will permit continuous operation of such a system.

Another object of my invention is to provide a controlling device which will be simple in construction, efficient in operation, and which may be expeditiously installed.

15 Other objects will appear hereinafter.

The invention consists in the novel combination and arrangement of parts to be herein-after described and claimed.

The invention will be best understood by 20 reference to the accompanying drawings, showing the preferred form of construction and in which:

Fig. 1 is a side view of my improved apparatus, partly in elevation and partly in 25 section;

Fig. 2 is a detail view taken on the line 2—2 of Fig. 1; and

Fig. 3 is a sectional detail view taken on the line 3—3 of Fig. 1.

30 The preferred embodiment of my invention illustrated in the drawing comprises a pressure operated device which includes a cylinder 10 in which a piston 11 is slidably mounted. The lower part of the cylinder 10 includes an inlet 12 in which a pipe 13 is screw threadedly mounted. The pipe 13 terminates in a hand operated valve 14, the purpose of which is brought out hereinafter. Connected to the valve 14 is the pipe 15 which, 35 in the present instance, is directed to the tank of a vacuum cleaning system, but it is to be understood that this pipe might be directed to any suitable container wherein a vacuum is to be maintained. The embodiment of my 40 invention illustrated herein is adapted to be actuated by varying degrees of vacuum, but it is to be understood that certain changes might be made which would be apparent to anyone skilled in the art that which would permit the 45 employment of the device in connection with a device containing pressure. Hereinafter I refer to the just described mechanism as a 50 pressure operated device for it is apparent

that for varying degrees of vacuum will permit normal air pressure to operate the device. 55 As stated, the pipe 15 is directed to a container 16 which constitutes the tank of a vacuum cleaning system of the permanently installed type. The end of the cylinder 10 opposite the opening 12 is provided with a series 60 of openings 17 which permit normal air pressure to enter the interior of the cylinder 10 above the piston 11. Brackets such as 18 are provided on the cylinder 10 to facilitate the mounting thereof in any desired location. 65

The operation of the device thus far described is as follows:

As the amount of vacuum in the container 16 varies it will also vary in the cylinder 10 in the area below the piston 11 for this area is 70 connected to the container 16 through the pipes 13 and 15 and the valve 14. As the vacuum varies, air pressure will enter cylinder 10 above the piston 11 and will actuate said piston proportionate to the degree of vacuum 75 below said piston.

Connected to the upper end of the piston 11 is a rod 20, which protrudes through an opening in the walls of the cylinder 10. If desired this rod 20 may be constructed of any 80 suitable length, but I find it preferable to shorten it and to arrange the rod in the following manner. As clearly shown in Fig. 1, I have arranged the rod 20 so that it embodies a hollow center, thus forming a construction 85 analogous to a pipe and I preferably provide a series of screw threads on the inner side at the outer end of the rod 20. A rod 21 is provided at one end with screw threads adapted to engage screw threads in the end of rod 20. 90 The upper end of the rod 21 protrudes through a guiding hole 22 in a bracket 23, which is mounted in any suitable manner in alignment with the cylinder 10. This end of the rod 21 carries screw threads adapted to be 95 engaged by a nut 24 and a lock-nut 25. Extending between the nut 24 and the bracket 23 is a spring 26, which is disposed around the rod 21 and is adapted to force said rod upwardly against the air pressure on piston 11 100 through the holes 17. Mounted on the rod 21 between the bracket 23 and the rod 20 are stop members 27 and 28 which have screw threaded portions which engage the screw threads at the respective ends of the rod 21. 105 Lock nuts 29 and 30 engage the stop members

27 and 28, respectively, and serve to lock said stop members in position. Slidably mounted on the rod 21 between said members 27 and 28 is a collar 31 having a pin 32 on its outer surface.

Mounted preferably in the position indicated in Fig. 1 is a base plate 33 having aligned pivots 34 and 35 thereon. Mounted on the pivots 34 and 35 for swinging movement are the members 36 and 37. Members 36 and 37 are provided with engaging gear segments 38 and 39 respectively. Opposite the gear segment 38, member 36 is provided with a projection 40 in which slot 41 is provided that is adapted to engage the pin 32 on the collar 31. The member 37 opposite the segment 39 has a projection 42. Mounted on the base plate 33 so as to engage the projection 42 are the adjustable stop members 43 and 44. It is apparent that movement of the collar 31 will be translated through the pin and slot connection, comprised of the pin 32 and the slot 41, through the projection 40, and gear segments 38 and 39, to the projection 42, the movement of which will be limited by the stops 43 and 44.

It is apparent that when the projection 40 moves in an upward direction, the projection 42 will also move in an upward direction. Referring to Fig. 3, it will be seen that pivots 45 and 46 are provided on the projections 40 and 42, respectively, and unitary with these pivots are the collars 49 and 50 that have openings therethrough extending at right angles to the pivots. Spacing collars 47 and 48 are provided between collars 49 and 50 and projections 40 and 42. Extending through the openings in the collars 49 and 50 is a rod 51 which is screw threaded at its ends and adapted for sliding movement through the openings in the collars 49 and 50. Nuts 54 and 55 are provided on the rod 51 and springs 56 and 57 are disposed, between said nuts and the collars, around the rod 51. It is apparent that when the projections 40 and 42 both move upwardly, the center distance between the pivots 45 and 46 will be reduced and therefore the springs 56 and 57 will be placed under tension. As soon as the point of equilibrium is passed the springs will snap the parts into engaging position. A similar action will take place as the projections 40 and 42 move downwardly. Such a device is understood in the art and is known as an over center device. This construction provides a quick acting apparatus and serves to hold the device in either its operative position or inoperative position.

At the outer end of the projection 42 a slot 58 is provided. The slot 58 engages a pin 58' carried on the rod 59 that is mounted for sliding movement in the brackets 60 and 61. A slidably mounted collar 62 of non-conductive material is provided on the rod 59 and fixedly mounted collars 63 and 64 are dis-

posed on each side of said collar 62. Springs 65 and 66 are disposed between the collars 63 and 62 and 64 and 62 so as to yieldably hold said collar 62 in position. Mounted on the collar 62 are the contact engaging members 67 and 68. In order to prevent undesired turning of the collar 62 the groove 52 is provided in the rod 59 in the pin 53 on the collar 62 rides in said groove. Mounted in the same plane as the brackets 60 and 61 is a contact carrying strip 69 on which the contacts 70 and 71 are provided which are adapted to be engaged by the contact engaging members 67 and 68. The control device just described is adapted for use to control an electric circuit, but it is to be understood that any other analogous control device might be substituted therefor, such as valve means and still not depart from the purview of my invention.

As stated the control device, heretofore described, is adapted to be used in connection with permanently installed vacuum cleaning systems. Devices of this kind include a tank and a means for exhausting the air therefrom. A suitable pipe system is then directed through the building in which the vacuum cleaning system is contained and cleaning means are adapted to be attached to various outlets in this pipe system. At the present time the exhausting means is continuously operated and in the event the vacuum becomes too high air is admitted into the system through a relief valve. This obviously reduces the efficiency of the system. I contemplate obviating this condition by connecting my control device so that the pipe 15 will be in communication with the main tank of such a system. Therefore, when the vacuum in such a system becomes high, the piston 11 will move to the lower part of the cylinder 10 in the manner described. This will move the rod 21 downwardly and will cause the stop member 27 to engage the collar 31, it being assumed that the projections 40 and 42 have been in their upper position and that the contact engaging members 67 and 68 have been engaging contacts 70 and 71. As the piston moves downwardly the stop 27 will force the collar 31 downwardly and when the projections 40 and 42 have passed the point of equilibrium, the springs 56 and 57 will act in the manner described and cause a snap movement of the parts controlled thereby, which will create a quick break between the contacting engaging members 67 and 68 and the contacts 70 and 71. Continued use of the system will lower the degree of vacuum in the tank 16 and therefore the piston 11 will be caused to rise, the spring 26 aiding this action. As soon as the projections 40 and 42 pass the point of equilibrium of the over center means the snap movement heretofore described will take place and will cause a quick make of the circuit controlling means. It is apparent that the stop members 43 and 44 will limit the

movement of the projection 42 and therefore control the distance through which the device will operate.

It is sometimes desired to obtain a high degree of vacuum in the tank 16. To provide for such a condition I have provided a valve 14 which is closed at such a time. In the pipe 13 the valve 19 is provided which is opened at such a time and this provides equal pressure on each side of the piston 11, and therefore permits the spring 26 to draw the rod 21 into its upper position and thus close the circuit controlling means. After the apparatus has operated for the desired length of time the valve 19 is closed and the valve 14 is opened which permits normal operation of the device.

While I have described my invention in connection with one form of apparatus with which it might be used, it is readily apparent that many other analogous uses might be made which would still not depart from the spirit and scope of my invention. As I have stated any type of control device might be substituted in place of the electrical one described.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A controlling device including, in combination, a pressure operated device, a rod operated by said device having spaced apart adjustable stops thereon, a member slidably mounted on said rod between said stops, a pair of pivotally mounted members including engaging segments and projections opposite said segments, a control device including fixed contact members and a slidably mounted rod carrying contact engaging members, the projection of one of said pivotally mounted members engaging said slidably mounted member on said first named rod, the projection of the other of said members being pivotally attached to the sliding rod of said control device.

2. A controlling device including, in combination, a pressure operated device, a rod operated by said device having spaced apart adjustable stops thereon, a member slidably mounted on said rod between said stops, a pair of pivotally mounted members including engaging segments and projections opposite said segments, the projection of one member being connected to said slidably mounted member, the projection of the other

member being pivotally attached to a control device, and over center means associated with said pivotally mounted members causing quick movement of the device at predetermined times during the operation thereof, and means for limiting movement of said projections.

3. A controlling device including in combination a pressure operator device, a rod operated by said device having spaced apart adjustable stops thereon, a member slidably mounted on said rod between said stops, a pair of pivotally mounted members including portions providing engaging segments and portions providing projections adapted to extend away from said portions providing said segments, collars on said projections adapted to have the openings therein extended toward each other, a bar extended through said collars having screw-threaded portions on the ends thereof extending beyond said collars, spring members disposed between said collars and nuts on said screw-threaded ends adapted to urge said pivotally mounted members so as to tend to move the projecting portions toward each other, one of said projecting portions having a slot formed in the end thereof, a pin on said slidably mounted member adapted to extend through said slot, and a control device adapted to be operated by the other of said projections.

4. A controlling device including in combination a pressure operator device, a rod operated by said device having spaced apart adjustable stops thereon, a member slidably mounted on said rod between said stops, a pair of pivotally mounted members including portions providing engaging segments and portions providing projections adapted to extend away from said portions providing said segments, collars on said projections adapted to have the openings therein extended toward each other, a bar extended through said collars having screw-threaded portions on the ends thereof extending beyond said collars, spring members disposed between said collars and nuts on said screw-threaded ends adapted to urge said pivotally mounted members so as to tend to move the projecting portions toward each other, one of said projections having a slot formed in the end thereof, a pin on said slidably mounted member adapted to extend through said slot, a control device adapted to be operated by the other of said projections, and adjustable stop members mounted on each side of said last named projection adapted to engage said projection whereby to limit the movement thereof.

5. A device of the class described including a supporting plate, studs mounted on said supporting plate in spaced apart relation, members pivotally mounted on said studs including portions providing segments adapted to be arranged in meshing relation and including projecting portions adapted to ex-

tend from said members opposite said segments, collars on said projections adapted to open toward each other, a bar extended through said collars having screw-threaded portions on the portions thereof disposed exteriorly of said collars, nut members on said screw-threaded end portions, spring members adapted to urge said pivotally mounted members so as to move the projections thereon toward each other, stop members adjustably mounted on said supporting plate on opposite sides of one of said projections adapted to limit the action of said spring members.

6. A device of the class described including a supporting plate, studs mounted on said supporting plate in spaced apart relation, members pivotally mounted on said studs including portions providing segments adapted to be arranged in meshing relation and including projecting portions adapted to extend from said members opposite said segments, collars on said projections adapted to open

toward each other, a bar extended through said collars having screw-threaded portions on the portions thereof disposed exteriorly of said collars, nut members on said screw-threaded end portions, spring members adapted to urge said pivotally mounted members so as to move the projections thereon toward each other, stop members adjustably mounted on said supporting plate on opposite sides of one of said projections adapted to limit the action of said spring members, in combination with a pressure operator device having a rod extending therefrom, adjustable stop members on said rod, a member slidable on said rod between said adjustable stop members, means for connecting one of said projections to said adjustable stop members, and means for connecting the other of said projections to a control device.

In testimony whereof I affix my signature.

FRANK E. LUMLEY.
